ADJUSTABLE SALES TAX STAMP HOLDER

Elmer C. Fisher, Columbus, Ohio

Application June 27, 1950, Serial No. 170,575

1 Claim. (Cl. 206—74)

1

This invention relates to stamp-dispensing devices, and more particularly to an adjustable dispensing device for sales tax stamps.

A main object of the invention is to provide a novel and improved sales tax stamp dispenser which is simple in construction, which provides means for holding sales tax stamps of various denominations, and which is readily adjustable for holding various quantities of sales tax stamps.

A further object of the invention is to provide an improved adjustable sales tax stamp dispenser which is very inexpensive to manufacture, which is compact in size, light in weight, which is neat in appearance, and which involves only a few parts.

Further objects and advantages of the invention will become apparent from the following description and claim, and from the accompanying drawings, wherein:

Figure 1 is a top plan view of an improved sales tax stamp dispenser constructed in accordance with the present invention;

Figure 2 is a cross-sectional view taken on line 2—2 of Figure 1;

Figure 3 is a cross-sectional view taken on line 3—3 of Figure 2;

Figure 4 is a fragmentary side elevational detail view of a rear end portion of the sales tax stamp dispenser of Figures 1 to 3.

Referring to the drawings, 11 designates a generally rectangular base to which are secured the longitudinally extending side walls 12 and 13, and the longitudinally extending intermediate partition wall 14 spaced midway between the side walls 12 and 13. Secured to one end of the base 11 and to the ends of the longitudinal walls 12, 13 and 14 is the transverse vertical end wall 15.

Designated respectively at 16, 17 and 18 are transverse block members slidably positioned between the longitudinal wall members 12 and 14, said transverse block members being formed at their side edges with horizontal ribs 19 and 20 which are slidably engaged in longitudinal grooves formed in the opposing vertical surfaces of the longitudinal wall members 12 and 14. Designated respectively at 21, 22 and 23 are similar transverse block members slidably positioned between the wall members 13 and 14 and formed with horizontal ribs 24 and 25 which are respectively slidably received in longitudinally extending grooves formed in the inwardly opposing wall surfaces of the longitudinal wall members 14 and 13. Designated respectively at 26 and 27 are transversely extending block mem-

bers positioned respectively between the longitudinal walls 12 and 14 and 14 and 13, as shown in Figure 3, the block member 28 being provided with the horizontal ribs 19 and 20 fitting the grooves in the inwardly opposing wall surfaces of the wall members 12 and 14, and the block member 27 being provided with the horizontal ribs 24 and 25 fitting in the grooves provided in the inwardly opposing wall surfaces of the wall members 14 and 13. The block members 26 and 27 are secured in stationary positions by transversely extending pin members 28 and 29 extending through the respective walls 12 and 13 and through the respective block members 26 and 27, as shown in Figure 3, and received in apertures formed in the intermediate, longitudinal wall member 14. The wall member 12 is formed with a plurality of transversely extending apertures, indicated at 30, and the intermediate, longitudinal wall member 14 is provided with a plurality of transversely extending apertures indicated at 31 aligned with the apertures 30, whereby the pin member 28 may be selectively engaged in any pair of aligned apertures 30 and 31. The longitudinal wall member 13 is similarly formed with apertures 32 aligned with the apertures 31 of the wall member 14, whereby the pin member 29 may be selectively engaged in any pair of the apertures 31 and 32.

Bearing between the block member 26 and the block member 18 are a concentrically arranged pair of springs 33 and 34, the inner spring 33 being seated in recesses formed in the opposing surfaces of the block members 26 and 28, as shown in Figure 2. The springs 33 and 34 act to bias the block member 18 to the right, as viewed in Figure 1, whereby pressure will be applied on the respective stacks of stamps, shown at 35, 36 and 37, interposed respectively between the block member 16 and the end wall 15, the block member 17 and the block member 16 and the block member 18 and the block member 17. A similar concentrically arranged pair of springs 38 and 39 is provided between the block members 27 and 23, as shown in Figure 2, whereby clamping pressure is applied to respective stacks of stamps 38, 39 and 40 positioned respectively between block member 21 and end wall 15, block member 22 and block member 21, and block member 23 and block member 22.

In order to load the dispensing device with stamps, the pin members 29 and 28 are withdrawn, each pin member being provided with a head or knob 41, to facilitate withdrawal and insertion thereof, and the required stamps are then

positioned between the block members and also between the block member 16 and end wall 15 and block member 21 and end wall 15, in the manner shown in Figures 1 and 2. The block members 26 and 27 are then secured in positions similar to that shown in Figures 1 and 2, by means of the locking pins 28 and 29, whereby the respective sets of springs 33 and 34 exert clamping pressure on the blocks 18 and 23, securing the lower portions of the stamps in the dispenser. It will be understood that the stamps are of the type wherein the upper portion is detached, leaving the lower or stub portion retained in the dispenser to indicate the number of stamps actually dispensed. From Figure 2 it will be seen that the upper portion of the stamps may be readily detached from the lower portion, particularly if the stamps are of the type wherein perforations are provided to define a tear line, said perforations being located substantially at the top plane of the dispensing device, whereby a clean and even tear will be obtained when the stamp is detached.

As shown in Figures 2 and 4, the top edges of the wall members 12, 13 and 14 are formed with transverse notches 42 overlying the respective openings in the wall members to provide a means of locating said openings when the pin members 28 and 29 are to be inserted in locking position. The top surfaces of the block members 26 and 27 are formed with similar transverse notches 42 overlying the pin members.

It will be apparent that any desired initial quantity of stamps may be inserted in the various compartments defined by the movable block members of the device, and that the quantity or number of stamps need not be the same in all compartments. By the above-described arrangement, the business concern dispensing the stamps need only purchase the quantities of stamps of each denomination required for a given period of time, thus minimizing the required financial investment in stamps, while still enabling supplemental quantities of stamps of various denominations to be inserted as required.

While a specific embodiment of an improved dispenser for sales tax stamps and the like has been disclosed in the foregoing description, it will be understood that various modifications within the spirit of the invention may occur to those skilled in the art. Therefore, it is intended that

no limitations be placed on the invention except as defined by the scope of the appended claim.

What is claimed is:

A device for holding stacks of stamps comprising, in combination, a body formed with an elongated main groove, first stationary abutment means secured to said body and extending transversely across one end portion of said main groove, a plurality of block members slidably positioned in said main groove, each block member being formed with longitudinal ribs on its opposite sides and the walls of the main groove being formed with longitudinal subsidiary grooves slidably receiving said ribs, a plurality of longitudinally spaced transverse holes extending through the opposite end portion of the main groove, a further block member located in said opposite end portion of said main groove, a removable transverse pin member extending through said body and through a selected hole in said further block member, and a pair of concentric coil springs positioned between said further block member and the adjacent one of said first-named block members, urging said adjacent one of the first-named block members toward the abutment means, whereby respective stacks of stamps of different denominations may be positioned between the adjacent respective block members and between the first stationary abutment means and the block member adjacent thereto, with the stamps extending a substantial distance upwardly beyond the block members and said abutment means, so that the upper portions of the stamps may be torn away while the lower portions of said stamps are held by the clamping force of the springs on the block members.

ELMER C. FISHER.
